CLAIM

The ornamental design for an integral videoconferencing system, as shown and described.

DESCRIPTION

FIG. 1 is a perspective view of the integral videoconferencing system showing our new design;
FIG. 2 is a front view of the integral videoconferencing system shown in FIG. 1;
FIG. 3 is a back view of the integral videoconferencing system shown in FIG. 1;
FIG. 4 is a right side view of the integral videoconferencing system shown in FIG. 1;
FIG. 5 is a left side view of the integral videoconferencing system shown in FIG. 1;
FIG. 6 is a top view of the integral videoconferencing system shown in FIG. 1; and.
FIG. 7 is a bottom view of the integral videoconferencing system shown in FIG. 1.
